UNITED STATES PATENT OFFICE.

WOLFGANG BECKER, OF CHICAGO, ILLINOIS.

GUIDE-PIN FOR PIANO-KEYS.

SPECIFICATION forming part of Letters Patent No. 366,615, dated July 12, 1887.

Application filed February 23, 1884. Serial No. 121,067. (No model.)

To all whom it may concern:

Be it known that I, WOLFGANG BECKER, a citizen of the United States, residing at Chicago, in the county of Cook and State of Illinois, have invented a new and useful Improvement in Pianos, of which the following is a specification.

This invention relates to the construction of the guide-pins employed with piano-keys at their front ends to regulate their movement when struck; and it consists in the novel features hereinafter set forth.

In the accompanying drawings, Figure 1 is a central vertical section of a key and key-slip, showing my invention; and Figs. 2, 3, and 4 are plan views of the guide-pin, showing different forms of the collar which may be employed.

In said drawings, A represents the piano-key, B the key-rail, and B' the slip. D is the guide-pin. The pin D consists of the upper guiding part, d, (which is oval in cross-section,) and the underscrew-threaded portion, d'. The former extends up into the recess a in the key, and the latter is inserted in the opening b in the key rail and slip. The pitch of the thread employed upon the stem should be fine, so that a half-turn of the pin will change its vertical position but very slightly, and I recommend that the stem be sufficiently long to insure sufficient friction against rotation. When thus constructed, it may be turned so as to cause the guiding part to bind against the sides of the recesses in the keys, and any loosening of the pin in its socket caused by such adjustment will have no ill effect.

The collar d², surrounding the pin at the junction of the guide and threaded portions, is intended to support the soft washer d³, usually employed heretofore to cushion the contact be-

tween the key and the key rail. Only a single 40 thickness of washer is ever required with this adjustable support, and thus the key meets with a firm resistance when the limit of its dip has been reached. If the pitch of the screw is fine, the half-turn of the pin, which may be the minimum rotation allowed, will not be found objectionable.

The pin may be turned in the adjustment either by providing the collar, as shown, with slots in its periphery, into which a convenient 50 tool may be inserted, or by making the periphery angular, as also shown, so that a wrench may be applied, or with holes into which hooks may be passed; or the sockets of the pins may be extended to the bottom of the slip or instrument, and a screw-driver be passed up from below, the end of the screw being nicked to receive it. This latter construction is illustrated in Fig. 1.

I claim—

1. The combination of a vertically-adjustable guide-pin adapted to receive a rotating tool, as set forth, and consisting of an oval head, a threaded stem, and cushion-supporting collar, and said cushion, with the piano-key and rail, 65 substantially as specified.

2. As a new manufacture, the adjustable guide-pin for regulating piano-keys having a guide portion, a threaded stem, and a collar between the guide portion and stem, said collar being adapted, as set forth, to receive an implement for rotating the pin, substantially as specified.

WOLFGANG BECKER.
